UNITED STATES PATENT OFFICE.

RICHARD WARD, OF NEW YORK, N. Y., ASSIGNOR TO LYMAN G. BLOOMINGDALE, OF NEW YORK, N. Y.

BRACKET FOR SUPPORTING AWNING-RODS.

SPECIFICATION forming part of Letters Patent No. 691,026, dated January 14, 1902.

Application filed April 11, 1901. Serial No. 55,288. (No model.)

To all whom it may concern:

Be it known that I, RICHARD WARD, a citizen of the United States, residing in the borough of Manhattan, city, county, and State 5 of New York, have invented certain new and useful Improvements in Brackets for Supporting Awning-Rods, of which the following is a specification.

My invention relates to awnings and similar devices; and it consists in the use of a rod 10 made of iron or other suitable material cast in one piece for the attachment of one end of the awning thereto and in the use in connection with said rod of devices made of metal 15 or other suitable material for holding and securing said rod, as hereinafter more particularly described.

The object of my invention is to provide a suitable support for the attachment of one 20 end of the awning and to provide means for readily holding and securing said support to the casing or framework of windows, doors, and other similar places, and thereby to avoid the attaching or securing of that end of the 25 awning to the casing or framework of the window, door, or building by means of staples or other devices, and by attaching pulleys used in connection with the awning to said support to avoid attaching pulleys to the casing 30 or framework of the window, door, or building, and to secure such an arrangement of parts used in connection with an awning that when the devices by means of which said support is held and secured to said casing or 35 framework are detached the said parts come down with and remain attached to the awning and do not remain affixed to the building, disfiguring it.

In the accompanying drawings, which illustrate 40 my invention, Figure 1 is a front view of a window rounded at the top and shows a curved metal rod R for the attachment of the top of the awning, held and secured by the metal devices or castings A, B, and A, which 45 devices are fastened by screws directly to the window-casing. Fig. 1 also shows pulleys used in connection with the awning firmly secured to the curved rod R by means of suitable clamps. Fig. 2 is a front view of a window 50 right-angled at the top and shows the straight metal rod R for the attachment of

the top of the awning held and secured by the metal devices or castings A and A. Fig. 2 likewise shows pulleys used in connection with the awning firmly secured by suitable 55 clamps to the metal rod R. Fig. 3 is a front view of a metal device or casting A and shows the curved rod R shown in Fig. 1 fitted into the socket of the device through the opening at the top, shown in Fig. 5. Fig. 4 is a side 60 view of the same device or casting A and shows the rod R fitted into the socket of the device through the opening at the top, as in Fig. 1, and also shows the socket of the device with the openings at the sides, whereby 65 the rod R can be fitted into the socket through an opening at the side, as shown in Figs. 2 and 5. Fig. 5 is a top view of the same device or casting A and shows the rod R fitted into the socket through the openings at the 70 side and shows also the opening to the socket from the top.

When it is desired to affix an awning to a window or door rounded at the top, an end of the canvas of the awning is hemmed around 75 or otherwise fastened to the curved rod R, to which the pulleys P are also firmly secured. The two ends of the curved rod R are then fitted through the openings at the top into the sockets of the two devices or castings A, 80 (shown in Fig. 1,) which are screwed or otherwise firmly fastened to the casing or framework of the window. The curved rod R also rests in the socket of the device or casting B, which is firmly fastened to the casing or 85 framework of the window, preferably at the highest point of the curve of the window. The curved rod R is secured in position by means of the set-screw S of the device or casting B. 90

When it is desired to affix an awning to a window or door which is right-angled at the top, an end of the canvas of the awning is hemmed around or otherwise fastened to the straight rod R, to which the pulleys P are 95 likewise firmly secured. The two ends of the straight rod are then fitted through the openings at the side into the sockets of the two devices or castings A and A, (shown in Fig. 2,) which are screwed or otherwise firmly fastened to the casing or framework of the window. The straight rod R is secured in posi- 100

tion by means of the set-screw S. (Shown in Fig. 2.)

The two ends of the curved rod R may if the rod be bent at each end be fitted into the 5 sockets of the two devices or castings A (shown in Fig. 1) through the openings at the side. In like manner the two ends of the straight rod R may if the rod be bent at each end be fitted into the sockets of the two de- 10 vices or castings (shown in Fig. 2) through the openings at the top.

When it is desired to remove an awning affixed to a window or door in the manner and by the means above described, it is necessary 15 only to detach the devices or castings A, B, and A, as shown in Fig. 1, or A and A, as shown in Fig. 2. When the devices mentioned are detached, the support or rod R will come down, carrying with it and still affixed 20 to it the awning, the pulleys, the ropes, and other parts which may be used in connection with the awning. Not only will it be found useful to have the support or rod R, the pulleys, ropes, and other parts remain affixed to 25 the canvas of the awning when it is desired again to affix the awning either to the same or to another window or door, but it is an advantage when removing the awning to remove with it the pulleys and other apparatus 30 in order that they may not remain affixed to the building to disfigure it.

Having described my invention, what I claim, and desire to secure by Letters Patent of the United States, is—

1. In an awning, a bracket device, made of 35 metal cast in one piece, provided with screw-holes and adapted to be attached by means of screws to a vertical, fixed support, such as a wall or window-casing, and provided with a fixed socket adapted to support and at either 40 side or at the top to receive the end of a curved or straight rod for the attachment and support of the cover of the awning, substantially as and for the purpose described.

2. In an awning, the combination of a single rod, adapted for the attachment and suitable for the support of the cover of the awning, and a bracket device made of metal cast in one piece provided with screw-holes and adapted to be attached by means of screws 45 to a vertical, fixed support, such as a wall or window-casing, and provided with a fixed socket adapted to support and at either side or at the top to receive said rod, substantially as and for the purpose described. 55

In testimony whereof I have hereunto set my hand, in the presence of two witnesses, this 10th day of April, 1901.

RICHARD WARD.
